UNITED STATES PATENT OFFICE.

JOHN T. STONEY, OF CLEVELAND, OHIO.

COLLAPSIBLE ARBOR.

Application filed March 29, 1920. Serial No. 369,560.

To all whom it may concern:

Be it known that I, JOHN T. STONEY, a citizen of the United States, residing at Cleveland, in the county of Cuyahoga and 5 State of Ohio, have invented a certain new and useful Improvement in Collapsible Arbors, of which the following is a full, clear, and exact description.

The present invention relates to the making of green sand cores for molding purposes and is more particularly directed toward a collapsible arbor for use in connection with the making of such green sand cores.

15 The present form of collapsible arbor is particularly useful in making the under, or supporting green sand core, in carrying out the method of molding set forth in my pending application Serial No. 281,945, filed 20 March 11th, 1919. However, I do not wish to be understood as in any way limiting the applicability of the present invention, as the collapsible arbor may be used in making green sand cores for use other than in carrying 25 out the particular molding method referred to.

Large cores for molding purposes are usually made of baked sand because in the baking a certain amount of inherent strength 30 is imparted to the core which enables it to support its own weight when the core is placed in a mold. A green sand core usually does not of itself, have sufficient inherent strength to permit of its being supported at its ends when placed within a mold and where a large core is made of green sand it is necessary to provide an interior or 35 strengthening structure which imparts inherent strength to the finished green sand 40 core.

It is a prime requisite of such a core support that it be removable from the inside of the casting when made, for reasons which are obvious and in the present form of arbor which is shown the arbor is collapsible 45 in a fashion which permits the removal of the arbor from within the casting without breaking the arbor.

Reference should be had to the accompanying drawings forming a part of this specification in which Fig. 1 is a top plan view of a core box having a collapsible arbor of the present invention mounted within the same; Fig. 2 is a side elevation of portions in 50 section of the arbor; Fig. 3 is a section along

the line 3—3 of Fig. 1; Fig. 4 is a section along the line 4—4 of Fig. 1; Fig. 5 is a top plan view of the modified form of arbor and core box; Fig. 6 is a transverse section showing the arbor in a core box with 60 sand; Fig. 7 is an end elevation with portions in section of the core box with arbor shown in Fig. 5; Fig. 8 is an elevation of the opposite end member for the core box, to that shown in Fig. 7. 65

Referring to the drawings, 1 indicates the wall of a core box which will of course be of proper configuration to mold a core of the required size and shape. Within the core box and extending from end to end thereof 70 is a bar 2. This bar from approximately the middle thereof toward one end is provided with side ledges 3 and 4 and the surface of the bar on the underside between the ledges is substantially semi-circular in form, 75 the upper part of the bar is in the instance shown flat. The portion of the bar which is provided with the ledges 3 and 4 is tapering, that is to say the ledges 3 and 4 diverge toward the end of the bar and likewise 80 the side walls of these ledges or shoulders also diverge.

Cooperating with the ledges 3 and 4 are plates which are indicated at 6. One of these plates is shown in Fig. 4 and as shown is 85 provided with a groove which conforms to the shoulders or ledges 3 and 4 and the semi-circular bottom part of the bar. The plate 6 may be slipped on to the bar 2 at the narrow part of the ledges 3 and 4 and moved 90 along the shoulders until it becomes seated and in tight contact with the bar 2. The various plates 6 which are shown have different sized openings adapted to cooperate with the bar 2 and hence when placed upon 95 the bar and moved along the bar as previously described they will assume positions upon the bar at different places between the ends thereof. This is illustrated in Fig. 1. A proper number of plates is provided so as 100 to give sufficient stiffening effect and strength to the body of green sand when packed around the plates 6.

The plates are provided with holes or openings such as indicated at 7 in Fig. 2 so 105 that when the green sand is packed around the plates, portions of the green sand will extend through the opening 7 and so form a close and intimate contact between the plates and the sand. 110

The forward portion of the bar 2 is also provided with shoulders 8 and 9 which are similar to the shoulders 3 and 4 and these shoulders are adapted to receive and support 5 a plate 10 in the same fashion as described with respect to the plate 6. The bar 2 as shown in the drawings does not have the shoulders 3 and 4 or the shoulders 8 and 9 extend throughout the length of the bar. 10 This, however, is merely one form of bar which may be used and it is entirely within the scope of the present invention to provide the shoulders 3 and 4 throughout the entire extent of the bar 2 and to have the side 15 walls of these shoulders arranged in the tapering fashion as before explained.

At the end of the bar 2 there is a plate 11. This is shown in elevation in Fig. 3. It is quite the same in many respects as the plates 20 6 and is secured on the bar 2 in precisely the same fashion but the plate adjacent its lower part is provided with a ledge 11^a which receives a bolt 12 having the head thereof on one side of the ledge and the 25 lower portion of the bolt is adapted to extend through the floor 3^a of the core box and when the bolt is so inserted the lower end of the bolt receives a nut 13 which securely fastens the end plate 11 to the core 30 box and so holds the arbor and the plates 6 carried thereby against movement within the core box. The arbor 2 at its opposite end has a plate 14 which is slidably mounted on the end of the arbor and is provided with 35 a bolt 15 having a nut 16 by which the plate is secured in the core box in precisely the same manner as described with respect to the bolt 12. Thus both ends of the arbor are anchored within the core box and are 40 rigidly held against movement not only during the time when the sand is packed in the core box but also is held against movement with respect to the core box when the core box is inverted for the purpose of withdrawing the core box from the core. Obviously the nuts 13 and 16 are removed 45 when the core box is withdrawn.

In using the arbor which has been described the plates 6 are arranged along the 50 arbor as indicated in the drawing and the end plates are secured within the core box, the green sand is then thrown in the box and compacted by methods which are well known. With the green sand suitably compacted the core box may be removed and the core positioned in the mold in a well known manner. Obviously the arbor being anchored in the core box permits the core box to be handled without danger of damaging 55 the core.

After casting has been made the arbor may be disassembled by driving the bar 2 in a direction which will loosen the plates 6. This then permits the withdrawal of the bar 60 2 through an end opening in the casting and

the subsequent removal of the plates which during the removal of the bar 2 have been slid off of the bar.

In Figs. 5 to 8 I have illustrated a different form of collapsible arbor which may be used in connection with a different type of core box, however, the same principle of construction may be utilized, as before described. In Figs. 5 to 8 of the drawings referred to there is shown a core box 10^a. 75

In Fig. 7 there is shown a core box 10^a. This core box at its ends is provided with substantially semicircular openings, one of which is indicated at 11^a, and at will be understood that at the opposite end there is 80 also a semi-circular opening of the same or different size to that shown in Fig. 7.

Cooperating with the openings in the ends of the core box are plates 12^a and 13^a, these plates being secured in their proper openings each by means of a bolt which occupies a slot in the lower part of the end member with which it is associated, and extends through an opening formed in the bottom of the core box. The bolt is slotted to 90 receive a wedge 14^a, which when driven home, forms an efficient securing means.

The end members 12^a and 13^a are provided with openings adjacent their upper parts which are adapted to receive the main member 95 of an arbor.

In the drawings, this main member of the arbor is indicated at 15^a, and is made triangular in shape, as indicated in Fig. 7, as are likewise the openings in the end plates for 100 the core box, as indicated at 12^b in Fig. 7.

The member 15^a tapers from one end to the other for a purpose which will be presently described.

Upon the member 15^a there are mounted a 105 number of plates such as indicated at 17^a. One of these plates is shown in elevation in Fig. 8, and as will be seen, each plate is provided with an opening such as indicated at 17^b which is of triangular shape in order 110 to permit the member 15^a to pass through the opening. Furthermore, each of the plates 17^a is provided with a plurality of openings such as indicated at 18^a.

The various plates 17^a are positioned upon 115 the member 15^a, and in order to hold these plates securely in their adjusted position, the size of the opening 17^b in the various plates varies in accordance with the position which it is to occupy upon the member 15^a, 120 the plates having the smaller size opening being toward the end of the member 15^a which co-operates with the end member 13^a of the core box.

The plates 13^a are secured in their proper 125 position by means of wedges such as indicated at 19^a, these wedges being driven through the opening in the plates 17^a and on top of the member 15^a. When the plates 17^a are placed to their proper position, the 130

box is filled with green sand to make the core, and in the making of this core the usual methods may be employed; that is to say, it may be jar rammed or hand rammed as may be desirable. The sand when compacted within the core box extends through the openings 18^a which are formed in the plates 17^a, thus exerting a tying or binding action to prevent the displacement of the sand with respect to the plates 17^a. The plates 17^a are preferably tapered, as indicated in Fig. 6, for the purpose of exerting a wedging action which will assist in holding the sand when the core box is inverted.

15 The arbor which comprises the member 15^a with the plates 17^a, is a collapsible arbor, that is to say, that when a completed mold has been made, in connection with which the core, such as shown in Fig. 6 has been utilized, the collapsible arbor, may be dis-assembled by driving the member 15^a from the plates 17^a, thus dis-assembling the arbor and permitting the individual parts thereof to be withdrawn from the interior of the cavity 25 of the casting.

Having described my invention, I claim:

1. A collapsible arbor comprising a rod which tapers from one end to the other, said rod being provided with a flat side, a plurality of plates, each of said plates being provided with an opening adapted to receive said rod, the openings in said plates being of different sizes, whereby the plates are positioned upon the rod when the rod is introduced to the openings in the plates, each of the openings in the plates being provided with a flat side which communicates with the flat side of the rod, thereby preventing rotation between the rod and the plates.

40 2. A collapsible core comprising a rod

which tapers from one end to the other, a plurality of plates, each plate being provided with an opening adapted to receive the said rod, the openings in said plates being of different sizes whereby the plates are positioned upon the rod when the rod and plates are assembled.

3. A collapsible core comprising a rod which at intervals throughout its length has portions of different cross-sectional area, a plurality of plates, each of which is provided with an opening to fit one of the aforesaid portions of the rod whereby the plates are spaced and positioned upon the rod.

4. A collapsible core comprising a rod having a tapered portion, said tapered portion being provided with ledges, a plurality of plates, each plate having an opening which co-operates with the ledges of the tapered portion, the said openings in the plates varying in size whereby the plates are positioned upon the tapered portion of the rod at different parts thereof.

5. A collapsible core comprising a rod, a plurality of plates adapted to be positioned at different points upon the rod, an end plate adjacent each end of the rod and means associated with each end plate for securing the same to a core box.

6. A collapsible core comprising a rod, a plurality of plates, each of said plates having an opening adapted to receive the said rod, end plates also having openings to receive the rod and means associated with each end plate for securing the same to a core box.

In testimony whereof, I hereunto affix my signature.

JOHN T. STONEY.
